PERMUTATION LOCK

Filed Sept. 18, 1935

UNITED STATES PATENT OFFICE

2,081,123

PERMUTATION LOCK

Elmer B. Stone, New Britain, Conn., assignor to
 The American Hardware Corporation, New
 Britain, Conn., a corporation of Connecticut

Application September 18, 1935, Serial No. 41,127

14 Claims. (Cl. 70—315)

My invention relates particularly to the type of permutation locks which are employed in connection with the doors of lockers and similar structures, and an object of my invention, among 5 others, is to provide a lock of this type by means of which a dial of maximum size may be used upon doors of minimum size; a further object of the invention is to provide a lock of this type by means of which the tumblers may be positioned with a minimum amount of movement of 10 the dial; a further object of the invention is to provide a lock of this type which may be readily opened should the combination be disarranged; a further object of the invention is to provide a 15 lock of this type in which the combination may be readily and conveniently changed; and a further object of the invention is to provide a lock of this kind that shall be simple in construction and particularly efficient in operation.

One form of a lock embodying my invention and in the construction and use of which the 20 objects herein set out, as well as others, may be attained is illustrated in the accompanying drawing in which—

Figure 1 is a face view of a portion of a set of lockers one of which is equipped with my improved lock.

Figure 2 is a side view of the same.

Figure 3 is a view on enlarged scale of a portion of a locker door equipped with my improved lock and with parts broken away to show construction.

Figure 4 is a view in section on a plane denoted by the dotted line 4—4 of Fig. 3.

Figure 5 is a view in section on a plane denoted by the dotted line 5—5 of Fig. 4.

Figure 6 is a view in section on a plane denoted by the dotted line 6—6 of Fig. 3, but on reduced scale and with parts broken away to show construction.

Figure 7 is an isometric perspective view of the tumbler members illustrating a way to adjust the tumblers if the combination be disarranged, the scale being enlarged.

Figure 8 is a detail view looking at the back of the lock case.

Figure 9 is a detail view on reduced scale showing the tumbler mechanism mounted on the inside cap that carries this mechanism.

Figure 10 is a view in section on a plane denoted by the dotted line 10—10 of Fig. 9.

The mechanism illustrated and described herein is the same in many instances as that forming the subject matter of my application S. No. 721,179, filed April 18, 1934, the present applica-

tion in fact being an improvement on the mechanism of said prior application. In the accompanying drawing the numeral 7 denotes the front plate of a set of lockers comprising openings with doors 8 closing such openings, one of such doors being shown in Fig. 1 as equipped with my improved lock. A handle 9 is slidably mounted upon the door for the purpose of latching and unlatching the fastening therefor, such fastening being controlled by my improved lock.

In prior structures, owing to the small space available on the front of these doors, the use of a dial of small dimensions has been compelled, and as lockers are frequently located in dark places, the use of such a small dial is objectionable owing to the difficulty in seeing the numbers upon it. However, these lockers and the doors are of standard construction and therefore the lock case and its mechanism is located in a definite position with respect to the handle 9, and this has compelled the use of the smaller dials hereinbefore referred to. By the use of my improved dial I am enabled, without changing the position of the lock case and its mechanism, to make use of a large dial, the only change required in the standard equipment being embodied in the dial structure, the lock case and its mechanism being undisturbed. These prior structures embody a bolt case 10 commonly constructed by bending metal at the edge of the door 8, as best shown in Fig. 5, such case extending from the top to the bottom of the door. A door bolt 11 of tubular form is slidably mounted within the case 10, the handle 9 being secured at its upper and lower ends to said bolt by means of projections 12 which extend through slots in the door for the purpose of permitting sliding movement of the handle.

A retainer 13 is attached to the door bolt withing the opening therein, the outturned end of the retainer projecting through a slot 14 in the wall of said bolt in position for its end to engage the edge of a slot 15 in the case 10, thereby holding the bolt in its unlocked position. A catch 16 secured inside of the front of the frame or front plate 7 projects in position to enter the slots 14—15, the upper edge of the slot 14 engaging within a notch in the catch to retain the door in its locked position, and as shown in Fig. 6. The door bolt is held in its locked position by a lock bolt 18 pivotally mounted within a lock case 17 secured to the rear face of the door 8 as by means of threaded studs and nuts, the nose of said lock bolt 18 extending through a slot in the side of the lock case and a slot 19 in the door 55

bolt 11, engagement in said slot locking the sliding door bolt against movement.

Movement of the lock bolt is controlled by means of a key plug 20 of any ordinary type and adapted to receive a key in the key slot 21, as a means to release the key plug for rotating movement. The lock bolt is also controlled in its movement by a set of tumblers rotatably mounted upon the key plug and heretofore operated in the usual manner by means of a dial mounted concentrically with said plug and through an opening in the center of which dial the key is inserted into said plug.

As hereinbefore explained the structure thus far described is of old and well-known form, the key within the key plug being made use of at any time to permit release of the nose on the locking bolt from engagement with the sliding door bolt.

The dial and tumblers are separately operated for the same purpose independently of the key.

In effecting my purpose, and in order to enable the use of a large dial without changing the position of the key plug and the tumblers within the lock, I pivotally mount my dial 22 upon a stud 23 projecting from a back plate 24 secured to the face of the door 8 as by means of threaded studs and nuts, and as shown in Fig. 4 of the drawing. A retaining ring in the shape of a flange 25 is formed at the periphery of the back plate. A gear ring 26 comprising an operating member is formed on the back of the dial, preferably integral therewith, teeth 27 on the inner edge of the ring 26 meshing with teeth on a pinion 28, constituting an operating member for the tumblers rotatably mounted upon the key plug 20. One of the tumblers 41 of a set of tumblers is rotated by the pinion 28, other tumblers of ordinary construction being provided with interengaging lugs and also with notches, the latter of which are caused to register to enable the locking bolt to be "thrown". This ordinary arrangement will be readily understood by those skilled in the art. A hole 29 is formed through the dial 22, through which hole access may be had to the key slot in the key plug 20. It will be understood that the locking bolt may be released for action by the use of a key at any time, whenever the dial is rotated to uncover the key plug, such lock feature being well understood by those skilled in the art, in the particular and novel arrangement shown herein this mechanism embodying a detent 40 movably mounted to enter the notches in the disk tumblers when said notches are aligned by operation of the dial 22, the tumbler 41 being rigidly connected to the pinion 28 as by means of interengaging lugs and notches, the other connected tumblers being shown in Fig. 7 of the drawing. The detent 40 is pivotally mounted on the locking bolt 18 hereinbefore mentioned and when in its locking position, that is, disengaged from the notches in the tumblers, a dog 42 is presented in its path of movement, thereby preventing movement of the locking bolt 18 and disengagement of its nose from the door bolt 11. However, the dog 42 is secured to a slide which is connected for operation by the key plug 20 so that when said plug is turned by the use of a key the dog is moved, thereby permitting movement of the detent 40 and consequent disengagement of the nose of the locking bolt 18 from the door bolt.

The tumbler mechanism including the actuating pinion, the tumblers and the spacers may be mounted on an inside cap 50 as shown in Figs. 9 and 10, this cap being located inside of the case

17 and having lips 52 resting on the side of the case underneath the cover 51 to close such case.

In the particular construction herein shown a positioning disk 30 of a more or less springy nature is located back of the dial 22 and in contact therewith, this disk being held against rotation in any suitable manner, as by lugs extending into notches in the back plate 24, and as shown in Fig. 3 of the drawing, said disk being in contact with the pinion 28. This pinion has a collar 31 projecting from its back face which extends through the back plate and door into the lock case, the outermost tumbler of the set of tumblers hereinbefore referred to being provided with lugs 32 with notches between them, said lugs and notches being engaged by similar lugs and notches formed on the collar 31, and as shown in Fig. 7 of the drawing.

It will be understood that the pinion 28 is so timed in its rotation with respect to the gear ring 26 that the proper number of rotations will be imparted to the tumblers in the movements of the dial to effect the final unlocking position of the tumblers as the dial is rotated to bring its graduation marks successively into registry with a pointer 33.

It will be noted that the gear ring 26 meshes with the pinion 28 and imparts a faster rate of rotation to said pinion and the tumblers connected therewith. These tumblers must be rotated one or more complete rotations, depending upon the number of tumblers employed and their position relatively to the tumbler operating member, as the pinion 28. In a permutation lock mechanism in common use three tumblers are employed and with these tumblers connected directly with the dial the latter must be rotated in opposite directions a number of times, three complete rotations in one direction being required, two complete rotations in the opposite direction, and one complete rotation in the same direction as the first movement. With my improved mechanism these pluralities of rotations of the tumblers in opposite directions may be obtained by a partial rotation only of the dial, the latter requiring a very limited movement to effect a number of rotations of the pinion 28 and the tumblers connected therewith. This comprises an important feature of my invention in my hereinbefore mentioned application.

To enable a change in the combination of the lock in a ready and accessible manner without disturbing the mechanism at the back, I mount the dial 22 so that it may be moved outwardly on or off from the stud 23 sufficiently to disengage the gear teeth 27 from the teeth of the pinion 28. To this end a key plug 34 is located in a socket in the knob 36 of the dial, this key plug being of any ordinary and well-known construction, pin tumblers being shown herein in Fig. 4 as a means for locking it against rotation. As shown an annular groove 35 is formed in the outer end of the stud 23 and a flange 37 on the back end of the key plug 34 engages within said groove. This flange is cut away on one side as at 38, as shown in dotted lines in Fig. 3, so that when the plug is turned to one position the flange will be released and the dial may be removed from the stud 23.

When it is desired to change the combination of the lock a key to fit the key plug 34 is employed to release the plug and enable it to be rotated, thereby disengaging the flange 37 from the annular groove 35 and enabling the dial to be moved outwardly thereby permitting the teeth

of the ring 26 to be disengaged from the teeth of the pinion 28. The dial may now be replaced in a different position with respect to the pinion 28 and to such extent, denoted by the graduations 5 on the dial, as may be desired, the teeth on the dial being reengaged with the teeth of the pinion 28, and the key plug 34 being turned to its locked position the dial will be securely held in place.

If, in attempting to change the combination, it 10 should be found that some mistake has been made and that the operation of the dial will not function to release the lock it will be obvious that if the old combination could be restored the lock would be in condition to function and then a 15 new attempt to change the lock could be made.

To effect this purpose I provide an indicator 39 in the shape of a notch in the gear 28 and another indicator 43 on the hub of the flange of the tumbler 41, and a similar indicator 44 on the hub 20 of the gear 28, and as shown in Fig. 7 of the drawing. All of the indicators when aligned and also when aligned with the pointer 33 will relatively locate the tumblers in their original positions the dial being then replaced with the zero mark 25 registering with said pointer. It will now be obvious that the old combination may be employed to unlock the lock and a new attempt may be made to change the combination.

In order to automatically disturb the tumblers 30 and throw them out of registry and thereby lock the mechanism without operation of the dial the detent 40 is provided with a finger 45 located for contact with a spring 46 when the locking bolt 18 is moved to unlocking position. When the 35 tumblers are in unlocking position the notches 47 are in registry, as shown in Fig. 7 and the detent 40 will have dropped into said notches. When the bolt 18 is now moved, as by operation of the door bolt 11, the finger 45 will pass under 40 the spring 46 placing the latter under tension tending to move the detent from said notches. The detent 40, having been lowered into the notches 47 as just described, will pass underneath and beyond the dog 42, carrying the notches to 45 the locking position shown in Fig. 8. As soon as the detent is released from the dog the action of the spring 46 on the finger 45 will cause the detent to be raised and as the nose of the locking bolt 18 is moved to its locking position the detent 50 40 will pass over the dog and into the position shown in Fig. 8. It will thus be seen that in the unlocking movement of the locking bolt 18 the notches in the tumblers will be disarranged and automatically placed in locking positions, but 55 that said bolt is permitted to return to its locked position at any time thereafter and while the tumblers are left in unlocked positions.

In order to enable the graduations on the dial to be placed in exact registry with the pointer 33 60 notches 48 are formed in the periphery of the gear ring 26, and as shown in Fig. 3 of the drawing, there being a notch for each of the graduations on the dial. This places a slight obstruction to rotation of the dial from each of the positions 65 where the graduations register with the pointer 33. A detent 49, preferably spring actuated, is located in a recess in the rib on the back plate 24, and as shown in Fig. 4 of the drawing, the nose of said detent being adapted to engage 70 the notches 48 for the purpose herein set forth.

It will be noted that by the use of this improved lock each tumbler is placed in its unlocking position by the use of a single designation. As an example, in prior permutation locks embodying 75 a number of tumblers, a plurality of designations

must be employed increasing with the number of tumblers except the first. The dial is given a number of complete rotations depending upon the tumbler to be positioned and there is therefore the designations on the dial and mental 5 designations denoting the number of rotations of the dial. With the present device a single designation only is employed, this being that denoting the position of the dial. The first tumbler is positioned by using the single designation and 10 the dial is then partially rotated to the next designation and then by a reverse movement to the next designation, and so on, a single designation being used in each instance.

In accordance with the provisions of the patent statutes I have described the principles of operation of my invention, together with the device which I now consider to represent the best embodiment thereof; but I desire to have it understood that the device shown is only illustrative 20 and that the invention may be carried out by other means and applied to uses other than those above set out.

I claim:

1. In a permutation lock, an actuating member 25 rotatably mounted to operate a set of tumblers, an operating member continuously operatively connected with said actuating member for each unlocking operation thereof, a dial operatively connected through said operating member with 30 said actuating member, a mount upon which said dial is movably mounted to temporarily sever its said connection and also for movement of the dial relatively to said actuating member to change the combination of the lock, and means other 35 than said dial for determining the relative operative positions of the dial and tumblers.

2. A permutation lock for a closure, said lock including a set of tumblers adapted to be operatively connected, a dial mounted on the outer 40 face of said closure, an actuating member operatively connected with said dial and with one of said tumblers, means accessible on said face of said door to effect disconnecting movement of said dial for changing the relative positions of 45 said actuating member and tumblers and means other than said dial for determining the relative operative positions of the dial and tumblers.

3. A permutation lock for a closure, said lock including a set of tumblers adapted to be operatively connected, a dial mounted on the outer 50 face of said closure, an actuating member operatively connected with said dial and with one of said tumblers, and interengaging members on said actuating member and tumblers for changing 55 their relative positions, means accessible on the face of said door to affect movement of said dial to change said relative positions of the actuating member and tumblers, and means other than said dial for determining the relative operative positions of the dial and tumblers.

4. A permutation lock including a set of tumblers adapted to be operatively connected, an actuating member operatively connected with one of said tumblers and having indicia for unlocking 65 operation of said member, means for changing the relative positions of said actuating member and tumblers, and means independent of said indicia for determining the original position of said actuating member.

5. A permutation lock including a set of tumblers adapted to be operatively connected, an actuating member operatively connected with one of said tumblers, means for changing the relative positions of said actuating member and 75

- tumblers, and indicating marks on said tumblers and cooperating actuating member for determining their original relative positions.
6. A permutation lock including a tumbler, a dial, an operative connection between said dial and tumbler for operation of the latter, means for removably retaining said dial in place, and key operated means for releasing said retaining member to permit removal of said dial to change its relative relation with respect to said tumbler.
7. A permutation lock including a tumbler, a rotatably mounted dial, an operative connection between said dial and tumbler for operation of the latter, a headed stud projecting into a recess in the dial, a releasing member carried by the dial to engage said stud to retain the dial in place, and means for disengaging said retaining member from said head to permit change of position of the dial relatively to said tumbler.
8. A permutation lock including a tumbler, a dial having a knob, an operative connection between said dial and tumbler for operation of the latter, a headed stud projecting into a recess in said dial, a key plug rotatably mounted in said knob and including a retaining member to engage the head of said stud, and means whereby a partial rotation of said retaining member by a key in said plug will release the retaining member from the head of said stud to permit change of position of said dial relatively to said tumbler.
9. A permutation lock including a tumbler, an actuating member operatively connected with said tumbler, a rotatably mounted dial operatively connected with said actuating member, means for rotatably changing the position of said dial relatively to said actuating member, and means for determining the original position of said actuating member relatively to said dial.
10. A permutation lock including a set of tumblers, an actuating member operatively connected with said tumblers, a dial operatively connected with said actuating member, means for rotatably changing the position of the dial relatively to said actuating member, and indicating marks on said actuating member and appurtenant to said dial to determine the original relative positions of said members.
11. A permutation lock for a closure, said lock including a set of tumblers adapted to be operatively connected, an actuating member operatively connected with one of said tumblers and having indicia for unlocking operation of said member, means for changing the relative positions of said actuating member and tumblers, and means accessible on the face of said closure for determining the original position of said actuating member independently of said indicia. 5
12. A permutation lock for a closure, said lock including a set of tumblers adapted to be operatively connected, an actuating member operatively connected with one of said tumblers and having indicia for unlocking operation of said member, means for changing the relative positions of said actuating member and tumblers, and cooperating indicating marks on said tumblers and actuating member and accessible from the front face of said closure for determining 10 their original relative positions.
13. A permutation lock for a closure, said lock including a tumbler, an actuating member operatively connected with said tumbler, a rotatably mounted dial operatively connected with said actuating member and having indicia thereon for unlocking operation of said tumbler, means for rotatably changing the position of said dial relatively to said actuating member, and means accessible from the front face of said closure for 15 determining the original position of said actuating member relatively to said dial. 30
14. A permutation lock for a closure, said lock including a set of tumblers, an actuating member operatively connected with said tumblers, a dial operatively connected with said actuating member and having indicia thereon for unlocking operation of said tumblers, means independent of said indicia for rotatably changing the position 35 of the dial relatively to said actuating member, and indicating marks on said actuating member and appurtenant to said dial and independent of said indicia to determine the original relative positions of the members. 40

ELMER B. STONE. 45
